UNITED STATES PATENT OFFICE.

WILLIAM H. LEIMAN AND GEORGE W. LEIMAN, OF NEW YORK, N. Y.

BUTTON-BORING MACHINE.

SPECIFICATION forming part of Letters Patent No. 603,854, dated May 10, 1898.

Application filed January 13, 1898. Serial No. 666,529. (No model.)

To all whom it may concern:

Be it known that we, WILLIAM H. LEIMAN and GEORGE W. LEIMAN, citizens of the United States, and residents of New York, in 5 the county and State of New York, have invented a new and useful Improvement in Button-Boring Machines, of which the following is a specification.

Our invention relates to an improvement 10 in button-boring machines, with the object in view of providing simple and effective means for changing the position of the button with respect to the boring-tool and for ejecting and supporting the button.

15 A practical embodiment of our invention is represented in the accompanying drawings, in which—

Figure 1 is a view of the machine, partly in side elevation and partly in longitudinal vertical section. Fig. 2 is a top plan view. Fig. 3 is a view in detail of the button holding and ejecting mechanism, showing the two parts in the position which they assume when a bored button has been ejected and when a button 25 to be bored is to be placed in position. Fig. 4 is an end view of the button holding and ejecting mechanism, and Fig. 5 is a transverse section through the line 5 5 of Fig. 2.

The base of the machine is denoted by A. 30 At one end of the base standards B B' are fixed, carrying in their upper ends the spindle b, to which the chuck b' is secured for holding the boring-tool b². The spindle b is rotated by means of a belt-pulley b³, driven 35 from a suitable source of power. (Not shown.) At the opposite end of the base A there is fixed a plate C, provided with a bifurcated standard C', in the branches of which a hollow shaft D is mounted and arranged to be 40 continuously driven by a pulley E thereon.

The hollow shaft D carries on its end toward the boring-tool an annular clutch member F, so connected with the hollow shaft as to rotate therewith—as, for example, by an 45 ordinary feather and groove—while permitted to slide on the shaft against the tension of a spring G, interposed between the clutch member F and the standard C'.

Within the hollow shaft D there is a stop- 50 rod d, which has a screw-threaded engagement with the interior of the shaft D throughout a portion of its length, as at d', and ex-

tends through to the end of the shaft which carries the clutch member for the purpose of forming a stop to the movement of the button-holder, as will hereinafter more particularly appear. The rod d is provided with a jam-nut d² for holding it in the desired adjustment.

A second bifurcated standard C² is fixed to 60 the plate C intermediate of the boring-tool and the drive-shaft D and has mounted in its branches the longitudinally-reciprocating and rotary hollow shaft H, carrying on its end toward the shaft D the clutch member F', 65 adapted to coact with the clutch member F to impart a rotary movement to the shaft H when such movement is desired. The shaft H has a grooved collar h fixed thereon, which receives studs i on the opposite branches of 70 an operating-lever I, pivoted to the standard C² at i'. The operating-lever I serves to force the shaft H bodily back and forth in a longitudinal direction toward and away from the 75 boring-tool and toward and away from the clutch member F.

Within the hollow shaft H there is located a rod or bar K, having its end toward the boring-tool split, in the present instance divided into quadrants by slits k, extending a considerable distance back from its head. Its head k', in which the button to be bored is received and held, is enlarged, the exterior being of tapered form, as shown at k², so that as the rod is moved toward the left as the drawing 85 is held the tapered portion k² will engage the inner surface of the hollow shaft H and close the sections of the split end of the tool, so as to grip the button tightly in the end. The bar K is further provided with an interior 90 bore k³, (see Fig. 3,) extending a considerable distance from its receiving end, and in the said bore k³ there is located a spring k⁴, having at its outer end a disk k⁵, which under the tension of the spring normally extends outwardly 95 partially across the space which the button to be bored occupies when held in the receiver. When the button is put in position, the disk k⁵ is forced back against the tension of the spring k⁴; but when the holder is slid to the right to 100 release its grip upon the button the disk k⁵ is pushed outwardly and serves to promptly free the button from the holder and cause it to drop out of the way. The disk k⁵ also

serves as a support for the button to prevent its chipping on its back as the holes are being bored.

A spring L is interposed between an abutment h^1 on the interior of the shaft H and an abutment k^6 on the rod or bar K, tending to hold the rod or bar K at the limit of its movement withdrawn toward the left within the shaft H.

10 For the purpose of arresting the rotary movement of the shaft H, carrying the button to be bored, in the proper positions to receive the action of the boring-tool we provide the shaft H with a pin or abutment h^2 , and to the 15 supporting-standard C² we pivot stop-dogs h^3 —in the present instance four—arranged at a quadrant's distance apart and capable of being swung back out of position to engage the pin h^2 when for any reason the number of 20 holes to be bored is less than four.

To hold the stop-dogs h^3 down in position or up out of, as the case may be, we provide a spring-band h^4 , having one of its ends turned upwardly to form a handle h^5 for operating it. A little space is left between the adjacent ends of the spring-band h^4 , as clearly indicated in Fig. 5, so that when this space is brought into position to register with one 25 of the stop-dogs h^3 the latter may be swung up away from the shaft H, and the split band h^4 may then be slid around into position to hold it out of engagement with the shaft.

The free ends of the dogs h^3 are beveled, as shown at h^6 , causing the pin h^2 to free itself 30 from the dog when the shaft H is reciprocated for the purpose of rotating it into a position to receive the boring-tool for the successive 35 perforations.

The shaft H is also provided with a pin or 40 stud h^7 , which coacts with the bevel-faced teeth c on a sleeve c', which projects from the supporting-standard C² toward the clutch member F'. The sleeve c' is provided with slots c² at intervals corresponding to the holding-dogs h^8 , which slots c² are adapted to receive the pin or stud h^7 while the tool is 45 operating upon the button to hold the button against rotary displacement. The bevel-faced teeth c serve to direct the pin h^7 to the slot c² and serve to adjust the shaft H, and hence the button, exactly in the desired position after the shaft has been rotated from one 50 position to another.

In operation the operating-lever I is swung 55 by its handle to the left as the drawing is held, forcing the end of the bar K into contact with the end of the adjustable stop d, thereby pushing the bar K to the right and leaving its split holding end free to expand 60 for the reception of a button.

By bringing the clutch member F' into engagement with the clutch member F the shaft H is rotated until the pin h^2 engages one of the stop-dogs h^3 . A button to be bored is 65 then placed in the receiving end of the bar K, and the handle of the lever I is swung to the right, permitting the spring L to withdraw

the bar K into the shaft H to clamp the button in position and finally bringing the button into contact with the boring-tool b². During 70

the boring operation the disk k⁵ forms a backing for the central portion of the button and prevents it from splitting. As soon as the one hole is bored the handle I is swung to the left to bring the clutch member F' into engagement with the clutch member F to rotate the shaft H into position to receive again the action of the boring-tool, but not sufficiently far to cause the stop d to push the bar K and release the button, when the handle of the lever is again swung to the right and another hole bored, and this is repeated until the button has been bored and is ready to be ejected, when the handle I is swung to the limit of its movement to the left, forcing the bar K out 85 of its position within the shaft H sufficiently to permit its head to expand and the ejecting-spring k³ to give the bored button a push. During this operation it is important to observe that when the shaft H is being slid 90 to the right to bring the button into engagement with the boring-tool the beveled face of the tooth c served to rock the shaft just enough to bring the stop h^2 into alignment with the dog h^3 , so that when the return movement of the shaft took place the beveled end of the dog operated upon the stop h^2 to cause it to return on the opposite side of the dog h^3 from that in which it advanced toward the 95 boring-tool, and hence leaving the shaft H 100 free to rotate until interrupted by the succeeding dog.

It is obvious that changes might be resorted to in the form and arrangement of the several parts without departing from the spirit and scope of our invention. Hence we do not wish to limit ourselves strictly to the structure herein set forth; but

What we claim is—

1. The combination with the holder and means for reciprocating it in a longitudinal direction, of a continuously-rotating shaft and means for temporarily clutching the holder to and releasing it from the shaft to change the position of the button, substantially as set forth.

2. The combination with the button-holder and means for rotating it, of stop-dogs for arresting the rotary movement of the holder and means for bringing different numbers of the dogs into operative position relative to the holder, substantially as set forth.

3. The combination with the holder and means for rotating it, of stop-dogs pivoted in position to swing into and out of operative position and a spring-band for holding them in and out of operative position, at pleasure, substantially as set forth.

4. The combination with the holder and means for rotating it, of a stop-dog having a beveled end, a cam, stops on the shaft in position to coact with the beveled end of the dog and with the cam to free the shaft from the dog and means for reciprocating the receiv-

ing-holder to bring the stops into engagement with the dog and cam to free the shaft from the dog and permit it to rotate, substantially as set forth.

5 5. The combination with the holder and means for reciprocating it in a longitudinal direction, of a stop on the shaft, a cam with which the stop engages and a slot for receiving the stop as it leaves the cam to lock the holder 10 against a rotary movement during the boring operation, substantially as set forth.

6. The combination with the longitudinally reciprocating and rotary holder, a rotary shaft and means for clutching the holder to and releasing it from the rotary shaft, of an adjustable stop seated in the rotary shaft for moving the holder relative to its support to release the button, substantially as set forth.

7. In a button-boring machine, the combination with the expansible and contractible holder, of an ejector seated within the holder, comprising a spring and a disk carried thereby, the said disk being adapted to press against the button when the holes are being bored to prevent the chipping of the button, substantially as set forth.

In testimony that we claim the foregoing as our invention we have signed our names, in presence of two witnesses, this 12th day of January, 1898.

WILLIAM H. LEIMAN.
GEORGE W. LEIMAN.
